UNITED STATES PATENT OFFICE.

KARL ROTTGARDT, OF DAHLEM, NEAR BERLIN, GERMANY, ASSIGNOR TO WESTINGHOUSE ELECTRIC & MANUFACTURING COMPANY, A CORPORATION OF PENNSYLVANIA.

PORTABLE POWER UNIT.

Application filed August 26, 1921. Serial No. 495,592.

To all whom it may concern:

Be it known that I, KARL ROTTGARDT, residing at Dahlem, near Berlin, Germany, Fontanestr. 14, have invented certain new and useful Improvements in Portable Power Units, for which application has been filed in the following countries: Germany, October 30, 1913; Belgium, June 29, 1920; Denmark, February 18, 1920; England, July 9, 1920; Finland, November 25, 1920; France, June 18, 1920; Holland, July 27, 1920; Italy, June 21, 1920; Norway, June 22, 1920; Poland, June 30, 1920; Spain, January 9, 1920; Sweden, December 30, 1919; Switzerland, July 22, 1920; Bohemia, June 17, 1920; Hungary, February, 19, 1914; So. Africa, September 27, 1920; Japan, February 15, 1921; Australia, July 10, 1920; and I do hereby declare the following to be a full, clear, and exact description of the invention, such as will enable others skilled in the art to which it appertains to make and use the same.

For portable stations for wireless telegraphy, carrier-stands of saddle or stool form have hitherto been employed, on to which the various station apparatus were fastened. Employment of such carrier-stands, which consist of a single unit, is however very disadvantageous for transport for various reasons, and as the utility of a portable station is very closely related to the method of transport employed, a transport apparatus which impedes the bearer, whether man or animal, or diminishes his capacity and mobility owing to other drawbacks, frequently impairs this utility.

Hitherto in stations carried by animals, for example, stands, with the station parts fastened thereon, have been strapped on to the pack saddle. Consequently the stands had to be so dimensioned that they would fit, for example, each horse. For this reason the width of the stand must be chosen comparatively large and the consequence of this is that when a slender animal is employed the load does not lie firmly on the saddle and swings to and fro especially at rapid rates of travel. The animal is therefore impeded and endangered. Moreover since the stand engages over the saddle, the center of gravity of the load is comparatively high and unfavourably placed. The result is that removal of the load and especially putting

the load on the saddle usually cause difficulties because when the load is lifted on, which must be effected either over the head of the animal or from behind, the animals become restless, a drawback which may become difficult to deal with when rapid erection of the station is desired. Quite as little are to be guaranteed the stool-formed stands which, in the case of stations carried by men, consist of one rigid unit. They thus lead to the bearer being overloaded or render necessary an increased number of employees for the transport of the station.

All these drawbacks are obviated by the following transporting device. There are employed not carrier-stands, which consist of a rigid whole, but separate carrier-frames on to which are fastened the station parts. These frames are transported individually and united to form a rigid stand only for operating the station. A special construction of the frames renders it possible to effect this union into a rigid stand and resolution into its various parts with very little handling.

In the accompanying drawings: 80

Fig. 1^a is a side elevation,

Fig. 1^b is an elevation of the opposite side,

Fig. 1^c is an end elevation of the apparatus in condition for transportation,

Fig. 1^d is an end view of the apparatus 85 when erected ready for operation,

Fig. 2^a is a detail view of the motor frame,

Fig. 2^b is a top plan view of the generator, 90 and

Fig. 2^c is a side view of the two frames united for operation.

In Fig. 1^c is illustrated by way of example the machine-saddle of a station to be borne by an animal. Fig. 1^a shows the motor side and Fig. 1^b the generator side. The driving motor 5 is built rigidly in the frame 1. For transport the frame is suspended from and firmly strapped, in the position shown in Fig. 1^c, in a holder 7 arranged on the sides of the saddle. The generator frame is carried in similar manner. Its frame is indicated by 2, the generator itself by 6. For operation, the two separate frames are lifted from the saddle, the extensions 3, 4 which fit together, are inserted the one into the other, and fastened by a clamping screw and in this way a

rigid operating stand (Fig. 1^a) is produced.

The advantages of this device are as follows. The various frames rest always firmly on the pack saddle independently of the size and strength of the carrying animal. The centre of gravity of the load may be located as low as seems desirable without enlarging the stand and augmenting the load. Also for rapid travel there is no swinging of the load to endanger the animal or apparatus. Moreover the laying-on and removal of the stand can be effected conveniently and quickly by one man by unstrapping the frames and taking them from the side of the saddle one after the other.

In portable stations to be carried by men, frames are likewise employed as carriers of the apparatus. The frames either are provided with pads so that they well fit the back of the bearer and can be carried like a knapsack or are fitted to specially formed cradles or baskets, on to which they are strapped for transport. Fig. 2 shows by way of example transport of the former kind, transport of the source of power being represented. Fig. 2^a shows the motor frame. 1 is the carrier-frame, 4 the motor and 6 a pad the bearer's back, indicated by

the line 7. Fig. 2^b shows the generator frame. Here 2 is the carrier-frame, 5 the generator and 6 a pad for the back.

For operation the two separate frames are here also united into a stand for erecting on the ground by means of clamping screws 35 and extensions 3, as is seen in Fig. 2^c.

Having now particularly described and ascertained the nature of my said invention and in what manner the same is to be performed I declare that what I claim is: 40

In a portable radio set, a prime-mover, a generator, a frame comprising two parts, one part carrying said prime mover and the other part carrying the generator, each of said parts having a pad conforming to the 45 shape of the side of a pack animal, each of said parts having feet with prongs for engaging the ground, said feet being on the side of the center of gravity of its part opposite the corresponding pad and means 50 above said pads for fastening said parts together, whereby when the set rests on said feet the weight of said prime mover and said generator will assist said fastening means. 55

In testimony whereof I affix my signature.

DR. KARL ROTTGARDT.
